US0D1038886S

(12) **United States Design Patent** (10) **Patent No.:** **US D1,038,886 S**
(45) **Date of Patent:** **** Aug. 13, 2024**

(54) **CONNECTOR**

(71) Applicant: **Jian Li**, Guangdong (CN)

(72) Inventor: **Jian Li**, Guangdong (CN)

(**) Term: **15 Years**

(21) Appl. No.: **29/914,498**

(22) Filed: **Oct. 18, 2023**

(30) **Foreign Application Priority Data**

Sep. 13, 2023 (CN) 202330597092.6

(51) **LOC (14) Cl.** **23-01**

(52) **U.S. Cl.**

USPC **D23/262**; D23/259; D23/261

(58) **Field of Classification Search**

(57) **CLAIM**

The ornamental design for a connector, as shown and described.

DESCRIPTION

FIG. 1 is a top perspective view of a connector showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The broken lines in the drawings illustrate portions of a connector that form no part of the claimed design.

1 Claim, 8 Drawing Sheets
